CLAIM

The ornamental design for a driving lever for car jack, as shown and described.

DESCRIPTION

FIG. 1 is a perspective view of a driving lever or car jack in accordance with the new design; and,

FIG. 2 is a perspective view thereof.

The broken line showing in the figures is included for the purpose of illustrating environment and forms no part of the claimed design.

1 Claim, 2 Drawing Sheets

FIG. 1

FIG. 2
